UNITED STATES PATENT OFFICE.

WILLIAM A. WEIGHTMAN AND CHARLES H. NITSCH, OF PHILADELPHIA, PENNSYLVANIA, ASSIGNORS TO STOKES & SMITH COMPANY, OF SUMMERDALE, PENNSYLVANIA, A CORPORATION OF PENNSYLVANIA.

SEALED WRAPPED PACKAGE.

1,249,571.

Specification of Letters Patent. Patented Dec. 11, 1917.

Application filed April 17, 1916. Serial No. 91,843.

To all whom it may concern:

Be it known that we, WILLIAM A. WEIGHTMAN and CHARLES H. NITSCH, residing at Philadelphia, in the county of 5 Philadelphia and State of Pennsylvania, have invented new and useful Improvements in Sealed Wrapped Packages, of which the following is a specification.

This invention relates to certain novel 10 and useful improvements in sealed wrapped packages.

In carrying out our invention we propose to provide a package of this type wherein the wrapper or cover blank which is preferably made of paper or other readily foldable material, is adherently attached by a suitable adhesive to all sides of the package, thereby presenting a smooth, continuous, uniform and attractive appearance, and at 20 the same time, the wrapper envelops the box or carton of the package in such manner as to close and seal the same against the entrance of dirt, dust, vermin, and foreign matter.

25 We also propose to provide a sealed wrapped package or box wherein the wrapper or cover blank is so shaped or formed that there is practically no waste of material in the cutting or making of the blank or wrapper, and at the same time the latter may be readily and conveniently applied to the box or carton with a minimum expenditure of time or labor. In this connection we wish to point out that our blank is 30 of such simple and convenient construction as to peculiarly adapt it for application to the box or carton of the package by means of an automatic wrapping machine, our wrapper being devoid of notches irregularly 35 shaped tongues, flaps and other portions which would tend to cause difficulty in its application to the box or carton.

Another object of our invention is the provision of a wrapped package of this character 45 wherein the complete area of the entire blank is but little more than the total area of all of the sides of the box or carton which it covers, so that not only is there no wastage of material, but when applied 50 the wrapper is devoid of all folds, seams and projections, especially at the corners and edges, with the result that such package will present an exceedingly neat, smooth and attractive appearance.

With the above recited objects and others 55 of a similar nature in view our invention consists in the construction, combination and arrangement of parts set forth in and falling within the scope of the appended claims.

In the accompanying drawings: 60

Figure 1 is a perspective view of the wrapper or cover blank of our package, the box or carton to be wrapped being indicated by dash lines and in position ready to be placed upon the wrapper. 65

Figs. 2 to 6 inclusive, are perspective views showing the package in various stages of the wrapping operation.

Fig. 7 is a perspective view of a completely wrapped package embodying our invention. 70

Referring now to the accompanying drawings in detail the letter A indicates the box or carton which is to be wrapped or covered, and in this instance such box or carton is 75 shown as of substantially rectangular box-like form. The letter B designates the cover blank or wrapper as an entirety, which in its unfolded position appears as shown in Fig. 1. The preferred form of the blank comprises a substantially rectangular body portion 1 which in the present instance is intended to cover or overlie and be adheringly attached to the bottom of the box A, and this body portion 1 is preferably of exactly 80 the same dimensions as the wall or face of the box it is to cover. Formed integral with the body portion 1 and at opposite longitudinal sides thereof are the side sections or wings 2—2 which in the present instance 85 are also substantially rectangular in form and are of the same dimensions as the sides of the box which they cover. Formed integral with one of the side sections or wings 2 is a top section 3, which is the same size as 90 the top of the box and is intended to be adheringly attached to and to cover such top, while the other side section or wing 2 of the wrapper blank is formed with a marginal edge portion or strip 4, which is of the 95 same dimension in one direction as the wall of the box upon which it lies and to which it is attached. In the manufacture of the wrapper we provide a substantially rectangular sheet of material such as is shown 100 in Fig. 1 and cut to the opposite side edge portions thereof to provide a series of parallel slits at each side edge portion, the slits

105

of the two series corresponding or alining as will be readily understood by reference to Fig. 1, these slits being shown at 5. By so slitting the wrapper we provide the latter 5 with laps which when the wrapper is applied will overlie the corners and ends of the box, and these laps, it will be noted, are formed without cutting notches or recesses in the blank, and therefore, there is no waste 10 of material, while the blank cutting operation is much simplified. When the blank is slit or cut, as shown in Fig. 1, it will result in providing the body portion 1 with the two end laps 6, while the two side sections or 15 wings 2 will each have a pair of end laps 7, and the top section 3 of the wrapper will be provided with a pair of end laps 8. The marginal edge portion or strip 4 will also be provided with a pair of end laps 9, but 20 if desired, these end laps 9 may be omitted, as they are not absolutely necessary.

In the formation of a sealed wrapped package made in accordance with our invention and embodying a wrapper such as has 25 been described the operation may proceed as follows: One face of the blank is first coated with a suitable paste or adhesive indicated by the letter C and upon the outspread blank is placed the box B, the bottom of the 30 box resting upon the adhesive coated face of the body portion 1 of the wrapper. The two side sections 2-2 of the wrapper are now folded against the adjacent side walls of the box and suitable pressure applied to 35 cause them to adhere thereto as shown by Fig. 2. The end laps 7 of the side sections or wings are now pressed inward against the ends of the box and caused to adhere thereto as shown in Fig. 3. Then the marginal 40 edge portion or strip 4 is folded over upon and pressed against the adjacent top portion of the package, and if the end laps 9 are provided for this marginal edge portion or strip 4, such laps 9 are folded down upon 45 and pressed against the adjacent end laps 7 now adhering to the ends of the box, as will be clearly understood by reference to Fig. 4. The top section 3 of the wrapper is now folded down upon and caused to adhere to 50 the top wall of the box, as shown in Fig. 5, and then the end laps 8 of this top section 3 may be folded and pressed against those portions of the wrapper which at this time adhere to the ends of the box, as will be understood by reference to Fig. 6. In the final 55 stage of completing the wrapping the end laps 6 of the body portion or bottom section 1 of the wrapper are folded inward against the ends of the package and overlie and adhere to the outer faces of the end laps 8 of the top section 3 of such wrapper. When 60 thus completed, the package will present the appearance shown in Fig. 7.

The above is a description of one manner 65 of conveniently and easily applying the

wrapper, but we wish it of course to be understood that we do not limit ourselves to this precise procedure or to the particular sequence of steps to be followed in folding and sealing the wrapper upon the box or 70 carton, as this may be varied, as will be readily appreciated.

In connection with our improved wrapper it will be noted that in its general appearance it resembles a rectangular sheet, 75 so that prior to its embodiment in the package it may be readily and conveniently printed with suitable advertising matter, or any desired data such as the name and address of the manufacturer of the merchandise, trade-marks and the like. The outer end laps of the package, which in the present instance comprise the end laps 6 of the body portion 1 are, it will be noted, of substantially the same dimensions as the 80 ends of the box, and consequently these end laps may constitute and serve as sealing labels, and may have suited printed matter thereon. Thus the necessity of employing separate seals and labels for the ends of the 85 box is avoided, and at same time the package is tightly sealed against the entrance of vermin, or any foreign substance which might injure or destroy the contained merchandise, especially should the latter be in the 90 nature of a food product.

While we have herein shown and described one preferred embodiment of our invention, we wish it to be understood that we do not confine ourselves to all the precise 100 details of construction herein set forth by way of illustration, as modification and variation may be made without departing from the spirit of the invention or exceeding the scope of the appended claims. 105

What we claim is:

1. As a new article of manufacture, a sealed wrapped package consisting of a box and of a one piece wrapper completely enveloping and adherently attached to all of 110 the exterior walls thereof, said wrapper comprising a rectangular blank having integrally united sections of uniform length adherently attached to the bottom, sides and top of the box, each of two opposite side 115 portions of the blank having a plurality of parallel slits cut therein forming between them a plurality of rectangular end laps which are folded over and adherently attached to the opposite ends of the package, 120 one pair of said laps at each end of the package being of substantially the same dimensions as the ends of the package and constituting sealing label sections for such ends of the package, each of said end laps being 125 of the same width as the section to which it is united.

2. As a new article of manufacture, a sealed wrapped package consisting of a box and a one piece wrapper completely en-

veloping and adherently attached to all of the exterior walls thereof, said wrapper comprising a substantially rectangular blank embodying a plurality of integrally 5 united sections adherently attached respectively to the bottom, sides and top of the box, one of the side sections of the wrapper having a longitudinally extending marginal strip integral therewith and folded 10 upon and adherently attached to an adjacent wall of the box, the bottom, side and top sections of the wrapper each having its end portions provided with rectangular end laps folded upon and adherently attached to the 15 ends of the box, the end laps of two of said sections being of substantially the same dimensions as the ends of the box and com- pletely covering and sealing such ends of the box, said end laps of all of the sections being formed by cutting opposite side portions of the rectangular blank to produce slits parallel throughout their length at each side portion of the blank, the parallel slits at one side of the blank alining with the corresponding parallel slits at the opposite sides of the blank. 20 25

In testimony whereof we have hereunto set our hands in the presence of two subscribing witnesses.
